United States Patent Office.

JAMES LEAK, OF GEDDES, NEW YORK, ASSIGNOR TO HIMSELF, THOMAS G. WHITE, AND WILLIAM HOLMES.

Design No. 4,449, dated November 1, 1870.

DESIGN FOR A FLOWER-POT.

The Schedule referred to in these Letters Patent and making part of the same.

To all whom it may concern:

Be it known that I, JAMES LEAK, of Geddes, Onondaga County, New York, assignor to myself and THOMAS G. WHITE, of Geddes aforesaid, and WILLIAM HOLMES, of Syracuse, New York, have invented and produced a new and original Design for a Flower-Pot, decorated with representations of trees and shrubs, substantially in the manner shown, of which the following is a specification.

The nature of my design is fully represented in the accompanying photographic illustrations, to which reference is made.

I claim as my invention—

The design for a flower-pot, decorated with representations of trees and shrubs substantially.

JAMES LEAK.
